UNITED STATES PATENT OFFICE

149,682

DESIGN FOR A PLATTER HOLDER

Peter Sampson, Chicago, Ill.

Application November 8, 1946, Serial No. 134,634

Term of patent 3½ years

(Cl. D44—10)

To all whom it may concern:

Be it known that I, Peter Sampson, a citizen of the United States, residing at 4222 West Congress Street, in the city of Chicago, county of Cook, and State of Illinois, have invented a new, original, and ornamental Design for a Platter Holder, of which the following is a specification, reference being had to the accompanying drawing forming a part thereof.

Fig. I is a perspective view of the platter holder embodying my design.

Fig. II is a face view.

Fig. III is a side elevational view.

Fig. IV is a top view.

I claim:

The ornamental design for a platter holder, substantially as shown.

PETER SAMPSON.
